UNITED STATES PATENT OFFICE.

JOHN MANOS, OF TORONTO, OHIO.

DESIGN FOR A GLASS SERVING DISH.

Application filed March 12, 1925. Serial No. 12,698. Term of patent 14 years.

To all whom it may concern:

Be it known that I, JOHN MANOS, a citizen of the United States of America, and resident of Toronto, county of Jefferson, and State of Ohio, have invented a new, original, and ornamental Design for a Glass Serving Dish, of which the following is a specification, reference being had to the accompanying drawings, in which—

I claim—

The ornamental design for a glass serving dish, as shown.

JOHN MANOS.
